UNITED STATES PATENT OFFICE.

HENRY P. VAN KEUREN, OF LANSING, MICHIGAN.

AIRPLANE.

1,346,570.

Specification of Letters Patent.

Patented July 13, 1920.

Application filed May 24, 1918. Serial No. 236,439.

To all whom it may concern:

Be it known that I, HENRY P. VAN KEUREN, captain, aviation section of the Signal Reserve Corps, Army of the United

5 States, and a resident of Lansing, in the county of Ingham, State of Michigan, have invented certain new and useful Improvements in Airplanes, of which the following is a specification.

10 My invention relates more particularly to improvements in airplanes of the military, tractor type, and it consists in the combinations, constructions, and arrangements of parts herein described and claimed.

15 One object of my invention is to combine in a single-seater airplane, intended primarily for use as a fighting scout or for use by staff observers, the following qualities in an extreme degree: agility or maneuver-

20 ability; high and low air speed; low landing speed; control of diving speed; high rate of climb; increased height of climb for a machine of its type; and best possible range of vision for the pilot.

25 All features of my invention are closely related and contribute directly to the attainment of the final object sought, which is to secure a military advantage over the enemy's air forces by the employment of airplanes of 30 superior performance.

Referring to the drawings which are illustrative, or merely by way of example, of a preferred embodiment of my invention, drawn to approximate proportions: Figure 35 1 is a plan view; Fig. 2 is a front elevation view; Fig. 3 is a side elevation; Fig. 4 is a section taken on line 4-4 of Fig. 1; Fig. 5 shows a preferred means of varying the angle of incidence of the main planes, herein referred to later, and Fig. 6 shows a portion 40 of the rudder and elevator control mechanism, also referred to later.

The fuselage, 9, is of rectangular section forward surmounted by a longitudinal semi-cylindrical removable engine hood, 10, which is as narrow as is possible to employ and at the same time suitably inclose the cylinder heads and manifolds of a six-cylinder, vertical, water cooled engine. The purpose of 45 such hood construction is to give the pilot as good a forward vision, along the sides of said hood, as is possible. At the front of the airplane, the flat sides and bottom of said fuselage are faired into a somewhat narrow and deep radiator, 11, and hood 10 is suitably rounded into the radiator, at its top

and sides; and filleted to the upper longerons, 12, of the fuselage, in such a manner as to produce a nose shape of least resistance on the fuselage unit.

60 Aft of the cockpit, 13, the lower longerons 14, are curved inwardly and joined into a keel 15, but the upper longerons 12, are curved gently inward and downward to a juncture at rudder post 16. Thus it is seen 65 that tail sections of the fuselage, such as Fig. 4, are triangular with base up and apex at the keel. The purpose of such construction of fuselage, as already described, is five-fold. 1st, it is desired to use a six-cylinder, vertical, water cooled engine of the geared type which is extremely simple, light, powerful, compact, reliable, and probably best adapted to methods of American manufacture. 2nd, it is desired to inclose such an engine in a 70 fuselage in as small a compass as is possible, in order to reduce fuselage sectional area to a minimum. 3rd, the pilot is so situated that while protected from the blast of the airscrew, his forward view is as large as 75 possible. 4th, the fuselage, which is of girder type and fabric covered, is reduced in weight and its strength and rigidity increased. 5th, where the rectangular section (included by the longerons at the cockpit) 80 fairs into the triangular tail section aft, a peculiarly advantageous warped curve is produced in the sides of the fuselage which, combined with the downward curve of the upper longerons, produces a marked effect 85 on the flying qualities of the airplane, in that the displaced air of the airscrew slip-stream is not only deflected downward by the warp of the fuselage sides, but is closed in along the keel thus providing a steady 90 effect upon the airplane in flight. Further, a considerable decrease in fuselage resistance is obtained by the form described due to a certain amount of lift imparted to the body by the deflected air through which it passes 95 and, also, to a propulsive force which may be likened to that which acts on the surf-board of a bather riding upon the crest of a wave.

100 In the effort to lessen the parasite resistance of the airplane of my design, I have inclosed both the rudder and elevator control cables 17 and 18 together with their crank arms, 19 and 20, in the stabilizing plane 21, and tail and vertical fin 22, as 110 shown in Fig. 6. Thus, rudder crank arm 19 swings inside horizontal stabilizing

plane 21, and elevator crank arm 20 swings inside the vertical fin 22 and the tail of fuselage 9, each control surface being operated in the usual manner from the pilot's 5 rudder bar and stick through their respective cables 17 and 18 and suitably disposed pulleys 23.

The main plane or upper wing 24 is of tapering plan form, with ends well raked. 10 Front and rear upper wing spars, 25 and 26, decrease in depth outwardly from the fuselage and are joined together at the wing tips. Sections of the wing also decrease in depth progressively as chord lengths decrease. At 15 intervals, suitable heavy wing ribs and diagonal internal drift wires are provided. At the cockpit, the main plane is cut away so that the pilot, whose seat is properly adjusted, may sit comfortably low and his eyes 20 be on a level just below the lower surface of the main plane. However, with senses alert for observation or combat, the pilot involuntarily sits more erect, in which case his eye 25 level is such that he may look over the main plane and in any direction overhead. His range of vision downwardly is blinded only by the narrow fuselage and by the narrow, tapering, inclined lower wings 27, which inclose and streamline a combined tension 30 and compression member 28, which takes the flying and landing load of the main plane in addition to the small flying load of said lower wing.

Ample surface, in ailerons 30, is provided 35 for the purpose of lateral control and by the combination of the leverages of rudder, elevators, and ailerons, as shown, the most difficult evolutions may be performed with great facility and speed. Aileron control 40 tubes 29 are inclosed within the upper wing.

Increased rate and height of climb, greater horizontal speed, slower landing speed, and control of diving speed are attained in the airplane of my invention as 45 compared to existing types of the same weight per unit area of supporting surface and weight per horsepower, by the employment of a variable angle of the main plane 24 in relation to the fuselage, 9. To this 50 end, the main plane is hinged to a vertical supporting member connected to the fuselage at 31 and also is hinged to the ends of members 28 of the tapering, inclined planes 27, at points 32-32. All hinges 32-55 31-32 lie on axis 33-33. By means of the vertically movable strut 34, the rear portion of the main plane is capable of being moved up or down in respect to axis 33-33, and by said movement the angle of the main 60 plane in respect to the horizontal axis of the fuselage, or the thrust line, may be varied at the will of the pilot from a slight negative angle to approximately fifteen degrees. For the main plane, an aerofoil section is used 65 wherein the location of the center of pres-

sure varies but slightly as the angle of incidence increases from nearly zero to fifteen degrees, but at the greater angle, both lift and resistance are greater.

In a climb, then, the pilot may increase 70 the angle of his main plane as he gains altitude and may always maintain his airplane in its most favorable climbing attitude, thus increasing the rate of climb and reaching a higher altitude due to increased lift and 75 less body drag.

In a long dive, a slower or higher speed may be attained by varying the angle of incidence, and by the same means a higher 80 horizontal speed and safer landing speed are possible.

In Fig. 5 are shown details of the angle of incidence control. Movable strut 34 passes through a close fitting slot 35 in member 36, and is provided at its lower 85 end with an integral portion having a relatively quick acting, multiple, self-locking thread 37. The hub of hand wheel 38, is tapped to fit said thread 37 and is further provided with spherical bearing surfaces 39 90 which seat in bracket portion 40 of member 36. A turn of the hand-wheel moves strut 34 through a comparatively large vertical distance so that the entire range of angle of incidence may be utilized quickly. 95

A relatively low and narrow chassis is employed, with small wheels set well forward of the center of gravity of the airplane. This feature lessens resistance and renders possible easier landings. 100

The airscrew is as short as can be efficiently used for the given power and speed. This occasions a somewhat wider blade but keeps down the peripheral speed.

Other advantages, such as ease of operation, simplicity of construction, reduced cost of manufacture, etc., will be apparent to those skilled in the art of flying machines. 105

What I claim is:

1. In an airplane, a hinged main supporting plane operatively controlled by the pilot, a fuselage inclosing an engine at the front portion thereof, a tractor airscrew, inclined side planes intersecting said hinged main supporting plane. 110

2. In an airplane, an airscrew at the front, a main upper supporting plane operatively hinged above a fuselage inclosing an engine forward and a cockpit in the central portion thereof, inclined lower planes 120 extending from the fuselage and intersecting said upper plane and hinged thereto, operatively movable control surfaces disposed in said main plane and at the rear of said fuselage, and means for taking-off and landing disposed below said fuselage. 125

3. In an airplane, an airscrew at the front, a main upper operatively hinged supporting plane tapering from center to raked tips, a fuselage disposed beneath said upper 130

- plane inclosing a power mechanism with its accessory parts and a pilot's cockpit, lower inclined planes disposed below said upper planes and extending from the lower part 5 of said fuselage outwardly to meet said upper plane tapering theretoward and hinged thereto, means for controlling stability and direction of flight, and means for starting off and landing.
- 10 4. In an airplane, the combination of an upper horizontal supporting wing capable of a controllable variation of angle in relation to a fuselage during flight, said fuselage being disposed below said wing, and inclined lower wing members extending from 15 said fuselage to said upper wing.
5. In an airplane, a main supporting

plane above a fuselage and hinged thereto, auxiliary supporting planes extending laterally from said fuselage to intersect said main plane toward its ends, hinges at said intersection, and means for controllable variation of the angle of said main plane with said fuselage.

6. In an airplane, a fuselage connected 20 by means of rigid members and inclined lower supporting planes to a main upper supporting plane and hinged thereto, control surfaces provided with unexposed means for said control.
